UNITED STATES PATENT OFFICE

JOSEPH PETER LUSCRI, OF CLEVELAND, OHIO

DESIGN FOR A COMPUTING-MACHINE HOUSING

Application filed May 27, 1929. Serial No. 31,418. Term of patent 14 years.

To all whom it may concern:

Be it known that I, JOSEPH PETER LUSCRI, a citizen of the United States, residing in Cleveland, in the county of Cuyahoga and State of Ohio, have invented a new, original, and ornamental Design for Computing-Machine Housing, of which the following is a specification, reference being had to the accompanying drawing, forming a part thereof.

Figure 1 is a top perspective view; and Figure 2 is an end elevational view of the housing of my new design.

I claim:

The ornamental design for a computing machine housing as shown.

JOSEPH PETER LUSCRI.
